(57) **CLAIM**

The ornamental design for a floodlight camera as shown and described.

DESCRIPTION

FIG. 1 is a top, front, right side perspective view of a floodlight camera showing our design, showing the camera with surface shading;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

In the drawings, the dash-dot-dash lines indicate the boundaries of the claim; and the evenly spaced broken lines depict unclaimed environment. The broken lines form no part of the claim.

1 Claim, 7 Drawing Sheets
